HANDLE FOR PERCUSSIVE DRILL

Frank A. Werstein, Long Beach, Ind.

Application September 3, 1957, Serial No. 47,590

Term of patent 14 years

(Cl. D54—14)

Fig. 1 is a top plan view of a handle for percussive drill embodying my new design;

Fig. 2 is a side elevational view of the handle; and

Fig. 3 is an end elevational view thereof as seen from the top of Fig. 2.

The dominant features of my design reside in the portions shown in full lines.

I claim:

The ornamental design for a handle for percussive drill, as shown and described.
